UNITED STATES PATENT OFFICE.

JOHN TOMKO AND CHARLES W. OPPENLANDER, OF CLEVELAND, OHIO.

ELECTRIC SIGNAL DEVICE.

1,236,625.

Specification of Letters Patent. Patented Aug. 14, 1917.

Application filed December 13, 1915. Serial No. 66,472.

To all whom it may concern:

Be it known that we, JOHN TOMKO and CHARLES W. OPPENLANDER, citizens of the United States, residing at Cleveland, in the 5 county of Cuyahoga and State of Ohio, have invented certain new and useful Improvements in Electric Signal Devices, of which the following is a specification.

This invention relates to electric semaphores or signal devices especially adapted and intended for use at street crossings, for the purpose of indicating the direction of travel, the intent being to stop traffic in one direction while it is passing in the other.

15 The device embodies a post on which are mounted swinging arms operated electrically to lift or fall at the will of a policeman or other operator.

In connection with the semaphores, night 20 signals are provided by means of lights carried by the arms, white lights showing in one direction, and red lights in the other, when the arms are down.

25 In the accompanying drawings—

Figure 1 is a perspective view of the device.

Fig. 2 is a diagram of the electric wiring of one of the arms.

30 Figs. 3 and 4 are elevations partly in section, showing the operating mechanism.

Fig. 5 is a detail of a clip.

The swinging arms 6 are mounted on a hollow post 7, or other suitable support, by pivots at 8, permitting the arms to swing 35 to either vertical or horizontal position.

Each arm is operated by means of an upper magnet 9 and lower magnet 10 the armatures of plungers 11 of which are guided in slotted brackets 12. These plungers are connected by rods 13 to slotted links 14 which are pivoted at 15 to the inner end of the arm 6, the connection between the rods 13 and the links 14 being made by pins 16 which are slidable in the slots 17 in the 45 links.

The arms are operated by means of the alternate application of current to the upper and lower magnets. When the arm is in horizontal position, as shown in Fig. 4 the 50 pin 16 on the lower connecting rod is at the lower end of the slot 17, and when the magnet 10 is energized its core 11 is pulled down, thereby lifting the outer end of the arm to vertical position, the pin 16 at the 55 end of the upper connecting rod 13 traveling during this action to the end of the slot

17 in the upper link 14. When the arm is to be dropped the upper magnet 9 is energized and the circuit of the lower magnet is broken, and the plunger 11 of the upper 60 magnet is pulled up thereby allowing or causing the arm 6 to drop to horizontal position. The arms 6 are almost counterbalanced, so that a pull in either direction will carry it to either position, the lost motion between the connecting rods 13 and the arm being taken up in the slotted links 14. A pin 18 acts as a stop for the upper link 14 to rest against when inactive.

A spring clip 19, attached to the side of 70 the post, is adapted to catch and hold the arm in vertical position and prevent the shock of sudden stoppage. This clip is shown located on the outside of the post, to catch the outer end of the arm.

75 In Fig. 3 the parts are shown with the arm in vertical position, and in Fig. 4 with the arm in horizontal position.

The arms are preferably made hollow, with a white glass 20 at the ends and red 80 glasses 21 at the sides, these glasses being illuminated by a lamp inside of the arms, with electrical connections to light the lamps when the arms drop. A bell 22 is also included in the circuit 23, and the bell and 85 lamp contacts are indicated at 24 and 25, for closing the appropriate circuits when the arms drop. The switches by which the magnets are controlled are indicated at 27 and 28, and will be suitably located for manipulation.

90 At night, when the arms are dropped the red lights show in one direction and the white lights in the opposite direction. If desired, suitable electric connections can be 95 made whereby the lights alone can be operated, without operation of the arms, all of the arms being allowed to remain down. A switch for such operation is indicated at 30.

The invention is not limited to the exact 100 construction shown, but may be varied within the scope of the following claims.

Having described our invention what we claim as new is:

1. In a signal, the combination of a support, an arm pivoted thereto, solenoids located at opposite sides of the arm, slotted links pivoted to the arm, and extending on opposite sides thereof respectively, and a rod pivotally connected to the core of each 105 solenoid and having a projection slidable in the slot of each link.

2. In a signal, the combination of a semaphore arm provided with luminous devices of different colors visible respectively from the sides and the end of the arm, and means actuated automatically by movement of the arm to simultaneously illuminate said devices, whereby one color will be shown in one direction and another color in the other.
3. In a signal, the combination of a hollow semaphore arm provided with different colored glasses visible from different direc-
10

tions, and means in the arm to illuminate all of said glasses when the arm is moved to a certain position.

In testimony whereof, we do affix our signatures in presence of two witnesses. 15

JOHN TOMKO.

CHARLES W. OPPENLANDER.
